UNITED STATES PATENT OFFICE.

PHILIP L. O'DONNELL AND GEORGE E. HIEBER, OF CINCINNATI, OHIO; SAID HIEBER
ASSIGNOR TO SAID O'DONNELL.

TAPING MECHANISM AND PROCESS OF REENFORCING MATERIAL FOR SHOES.

Application filed October 5, 1925. Serial No. 60,457.

Our invention relates to the general art of mechanism adapted to apply reenforcing tape to any articles and particularly relates to improved mechanism for applying tape in other than straight lines, especially to leather vamps, tips and the other parts of shoe uppers which require reenforcing.

It is the object of our invention to provide improved mechanism operating in timed relation to work feeding mechanism such as a sewing machine operated without the needle, which will automatically feed suitable taping material onto the work as it is fed through the machine.

It is further our object to provide cutting means operating in timed relation to the tape feeding mechanism which will snip with little cuts extending into the tape from the side, either one or both edges of the tape so that the tape will lie flat when applied in other than straight lines onto any given work.

It is our object to provide means to inhibit the cutting means at the will of an operator.

It is an object of our improved mechanism to provide a guard plate which will prevent the tape sticking to and being carried around on the tape feed roller. Finally it is our object to provide an improved mechanism operable under the presser foot and inner walking foot of a sewing machine which will provide from under the work a feeding mechanism operating in time with the snipping knives and the presser and walking foot.

The particular difficulties which have been encountered in connection with the use of the novel taping machine as disclosed in co-pending application Serial No. 662,134, filed September 11, 1923, as utilized for carrying out the process of reenforcing shoe vamps described in Patent No. 1,556,124, issued Oct. 6, 1925, are three. One difficulty has been the tape being fed over a rotary feed has sometimes caught in the rotating element and been carried around with it. Our novel guard plate prevents this difficulty. Another difficulty has been that the regular sewing machine under feed plate is difficult to install in connection with our improved mechanism for feeding and snipping the tape. Our novel underneath feed foot overcomes the mechanical difficulties involved in adapting the regular under feed plate of a

sewing machine with our improved mechanism for feeding and snipping the tape.

Finally the greatest improvement in our structure has been in the provision of a reciprocating cutter which snips the tape from a side edge so that the tape will always lie flat even when used on very acute bends in the work.

The side edge cutting mechanism enables the tape to be applied to the curve of a shoe vamp without the necessity of having to use scissors to snip the work afterward, which saves a great deal of hand labor with the consequent reduction in the cost of the shoes and further improved quality of the work done.

In combination with our mechanism we have provided a simple means of accomplishing an improved process of reenforcing shoes and leather which should be considered the most essential object of our invention.

Referring to the drawings in which we have illustrated our preferred mechanism:

Figure 1 is a side elevation of a sewing machine with the addition of our preferred improved mechanism.

Figure 2 is a top plan view.

Figure 3 is an end elevation of a portion of the mechanism showing the snipping mechanism.

Figure 4 is a side elevation of the parts shown in Figure 3.

Figure 5 is a side elevation of the entire assembly.

Figure 6 is a detail elevation showing the underneath feeding foot.

Figure 7 is a section along the lines 7-7 in Figure 6.

Figure 8 is a detail along the lines 8-8 in Figure 5.

Generally indicated at 1 is the frame of the machine which is mounted on a table 2 at which the operator sits. The mechanism is illustrated as being supplied with driving power from a motor 3. The presser foot shaft 4 is driven by a belt and pulley 5 and 6 respectively, and as shown in Figure 5 the shaft drives an eccentric stud 7 to which is connected the link 8 and the link is pivoted on a pin 9 held fast in the arm 10. The arm 10 has a nose 11 adapted to be engaged by a lift 12 and an arm 13 is pivoted on the arm 10. The arm 13 engages by clamping over the presser foot rod 14. A spring 15 on the presser foot rod is engaged by the arm 13

and also by the casing at the top of the machine through which casing is slidably set the end of the rod 14. The presser foot rod is thus operated so as to be lifted, with the 5 spring tensioned to move the foot to depressed position. The presser foot 16 is disposed on the end of the presser foot rod and is a slotted member. The walking foot, which is shown at 17, rests in the slot of the 10 presser foot and is mounted on a rod 18 which is pivoted as indicated at 19 to a link 20. The link 20 is also connected to the pivot of the arm 13 as indicated at 21.

The operation of the walking foot and the 15 presser foot is as follows: The eccentric stud at the top of the machine revolves thereby rocking the arm 10 and with it the link 20, so that the end of the link which is pivoted to the arm 18 is moved downwardly. When 20 the foot 17 contacts with the underneath feed foot, which will be described hereinafter, the pivot at 19 will permit the foot 17 to travel along with the underneath feed foot. At the 25 moment of contact of the walking foot with the underneath feed foot the pivot at 19 can no longer move downwardly so that the arm 10 is forced to rise carrying with it the arm 13 and the presser foot rod 14, the link 20 being also swung upwardly.

30 The cooperating operation of the under feeding foot is of course necessary for the successful feeding of both work and tape. The construction of the mechanism for operating the under feed foot is as follows: A shaft 22 is disposed under the frame of the machine and a silent chain drive 23 from the shaft 4 provides for its rotation. A cam finger 24 mounted on the shaft 22 (Figures 3, 6 and 7) is enclosed in an internal cam portion 25 on an underneath feed foot 26. This member is pivoted as shown at 27 to a 35 stationary link 28. The upper end 29 of the member is preferably roughened and the limit of movement of the roughened end is upward enough to contact with the walking foot 17 at which point the internal cam reaches a corner so that upward movement is limited and the two feet together advance the work and the tape disposed on the work. 40 This cycle of movement is repeated as the work and the tape are fed through the mechanism.

45 The taping supply may be as indicated with the tape formed into a roll 30 on a rotatably mounted spool 31. Feeding from the spool the tape passes preferably to a guide roller 32 also rotatably mounted and supported by a bracket 33 in which the roller is journaled. The adhesive surface of 50 the tape is on the outer side of the supply so that an unadhesive face passes over the roller 32. Another roller 34 which may as shown be a rotatable shaft is journaled in brackets 35 and driven by a pulley 36, driven by a belt 37, which is engaged about

a pulley 38 mounted on the presser foot shaft 4. A guard plate 39 with trunnion-like journals at the sides is loosely mounted on the shaft 34. The tape is withdrawn from the supply by the rotation of the shaft 34 70 to which the adhesive surface of the tape adheres sufficiently to exert a suitable withdrawing tension which unrolls the tape. The tape passes over the roller 34 in the position indicated in dotted lines in Figure 8 75 and the guard plate as will be obvious prevents the tape from sticking to the roller 34 and wrapping about it.

75 From the feed roller the tape passes over guide rollers 40 through the heating chamber 41 in which the adhesive is warmed just enough to stick tightly to the work. The tape is drawn with its adhesive face up to the feeding feet, being preferably tensioned through slotted guides 42 just before it 80 passes to the feeding feet.

85 The cutting device with which interspaced slits are snipped in a side edge of the tape is constructed as follows:—On the shaft 22 (Figures 3 and 4) a crank 43 is eccentrically mounted. The end of the crank is pivoted to a cross link 44 which is pivoted in a fixed link as at 45. The other end of the cross link 44 is pivoted to the base of a plunger rod 46; as the shaft 22 turns the plunger rod is oscillated up and down. The oscillating cutter knife 47 which is vertically mounted so as to move across the path of the tape is secured at its base to a rod 48 which is tensioned with a spring 49 toward a down position. The lower end of the rod 48 and the upper end of the plunger rod 46, are interspaced so that a clutch member 50, pivoted to a shifting rod 51, which is pivoted to a treadle member 52 is disposed in position 90 to be moved by an operator's knee into engaged position. It is preferable to have the clutch member out of engagement during the regular operation of the taping mechanism which may be provided by a spring 53 95 100 extending from the frame of the machine and tensioned to pull the treadle connecting link 54 to the left as shown in Figure 4. A cooperating knife 55 mounted in opposed position to the oscillating knife on the opposite side of the tape may be successfully used to make a clean cut in an edge of the 105 tape.

110 While in the foregoing disclosure we have only described one mechanism for snipping a side edge of the tape, it will be readily understood that modifications in the type of knife used by which slits may be made in the tape in any desired positions will readily occur to those skilled in the art. Our invention consists primarily in the idea of slitting the tape before its application to work, and also in providing suitable mechanism with which an operator may slit an 115 edge of the tape during any preferred in- 120 125 130

tervals while the tape is being applied. Referring to the Patent No. 1,596,124, issued Oct. 6, 1925, for processes of reenforcing shoe vamps, our invention is an improvement of this process and in the claims which follow it is our purposes not only to claim the improved mechanism herein described but also the process of slitting an edge of reenforcing tape prior to its application to leather for shoes.

Having thus described our invention, what we claim as new and desire to secure by Letters Patent, is:—

1. Mechanism for mechanically applying adhesive reenforcing tape to leather pieces comprising in combination with work feeding mechanism, a storage for tape, means for withdrawing tape from the storage, a guard for said means to prevent the tape sticking thereto, means for feeding the tape with the work through the work feeding means, and means for slitting an edge of the tape prior to its application to the work.

2. Mechanism for mechanically applying adhesive reenforcing tape to leather pieces comprising in combination with work feeding mechanism, a storage for tape, means for withdrawing tape from the storage, a guard for said means to prevent the tape sticking thereto, means for feeding the tape with the work through the work feeding means, and means for slitting an edge of the tape prior to its application to the work, with means for inhibiting said edge slitting means independent of the feeding means.

3. Mechanism for mechanically applying adhesive reenforcing tape to leather or substitutes therefor comprising in combination with work feeding mechanism, a storage for tape, means for applying the tape with the work through the work feeding means, means of unwinding the tape from the storage prior to its application to the work, means for preventing the tape from sticking to said last named means, a heated compartment through which the tape is guided prior to its application to the work and subsequent to its unwinding from the storage, and means for cutting with interspaced slits a side edge of the tape prior to its application to the work.

4. Mechanism for mechanically applying adhesive reenforcing tape to leather or substitutes therefor comprising in combination with work feeding mechanism, a storage for tape, means for applying the tape with the

work through the work feeding means, means of unwinding the tape from the storage prior to its application to the work, means for preventing the tape from sticking to said unwinding means, a heated compartment through which the tape is guided prior to its application to the work and subsequent to its unwinding from the storage, and means for cutting with interspaced slits a side edge of the tape prior to its application to the work, and means of inhibiting the cutting means.

5. In combination with work feeding mechanism consisting of a presser foot a walking foot with means of operating said foot and said walking foot, and means for withdrawing adhesive tape from a supply, cooperating mechanism for feeding adhesive reenforcing tape comprising a cam mounted on a rotatable shaft, a member linked to a stationary member, said member having an internal cam engaged with the cam on the shaft, the said member being pivotally mounted in said links and adapted with timed rotary movement of said shaft to feed the reenforcing tape under the work.

6. In combination with work feeding mechanism consisting of a presser foot a walking foot with means of operating said foot and said walking foot, and means for withdrawing tape from a supply, cooperating mechanism for feeding adhesive reenforcing tape comprising a cam mounted on a rotatable shaft, a member linked to a stationary member, said member having an internal cam engaged with the cam on the shaft, the said member being pivotally mounted in said links and adapted with timed rotary movement of said shaft to feed the reinforcing tape under the work, and means of snipping a side edge of the tape and means of disposing said tape in a curved line flat against the work.

7. Mechanism for applying adhesive reenforcing tape to shoes and leather comprising in combination with a supply for tape, means for applying the tape to articles to be reenforced, and a rotating member disposed between the supply and the applying means adapted to provide a loosened strip continuously to the applying means and a guard on the rotating member disposed in position to prevent the said tape being entwined about said rotating member.
